UNITED STATES PATENT OFFICE.

MOSES G. FARMER, OF NEW YORK, N. Y.

APPARATUS FOR FORMING WIRE BY ELECTROLYSIS.

SPECIFICATION forming part of Letters Patent No. 338,941, dated March 30, 1886.

Application filed June 13, 1885. Serial No. 168,638. (No model.)

To all whom it may concern:

Be it known that I, MOSSES G. FARMER, a citizen of the United States, residing in New York, in the county and State of New York, 5 have invented certain new and useful Improvements in Apparatus for Forming Wire by Electrolysis, of which the following is a specification.

My invention relates to the organization of 10 apparatus for forming copper and other wire by electro-deposition; and its object is to simplify the process and cheapen the cost of producing it.

In general terms the invention consists in 15 passing through one or more electro-deposition vats continuous wires of conducting material and depositing thereon by electrolysis pure copper or other metal or metals. After the wires have been thus increased in size to 20 any desired extent they are drawn down by the usual processes to the required size, and thus given a required degree of hardness. A sufficient quantity of the wire thus obtained may be employed as the foundation for 25 the succeeding deposition, providing homogeneous wire is to be formed, and in this manner a portion of the wire obtained from each treatment is used as the basis for the subsequent treatment.

It has been proposed to apply to lengths of 30 wire a single coating of metal by passing them once through a vat.

In another application of even date herewith, Serial No. 168,637, there is described an 35 apparatus for forming sheet metal by electricity, in some respects resembling that described in this application. The deposition, however, is in that instance made upon only one surface of the cathode, the other being coated with a 40 non-conductor.

In the accompanying drawings, illustrating 45 the invention, Figure 1 shows in vertical transverse section four vats and the connected apparatus, and Fig. 2 is a plan view of the vats.

Referring to the figures, B B B B represent 50 four electro-deposition vats, each of which is equipped with two systems of rollers, a a and A' A', across or between which there passes a series of wires, b b b, &c. The rollers are

preferably grooved, for the purpose of keeping the wires in position and out of contact with each other. The wires also extend beneath other guiding-rollers C² C² and C³, and as they pass these rollers they are pressed 55 down into the corresponding electro-deposition vat, B, by means of suitable rollers, C' C' C', &c. One of the rollers—C³, for instance—is provided with any suitable means for revolving it, and thus carrying the wires through 60 the vats. There may be one, two, or more vats B, as desired. Any or all of these rollers may be grooved, as found convenient and necessary, and one of them is driven by any suitable power. The wire as it passes through 65 the vat is designed to receive a deposit of copper or other metal, and for this purpose the vat contains an electrolyte consisting of a suitable solution of the metal. The negative pole of the generator or other suitable 70 source of electricity, E, is connected by a conductor, 1, with the series of rollers a or A' in each vat; or they may be, in any other convenient manner, connected with the conducting-wires b. The positive pole of the battery 75 is connected by a conductor, 2, with suitable anode-plates, d d and d' d', located in the deposition-vats. There are two series of anode-plates, one above and the other below the wires, and thus metal will be dissolved from 80 the anodes and deposited from the solution upon the wires evenly as they pass through the vat. The wires are moving continuously, and at each successive bath the different positions receive additional deposit, thus gradually increasing in size. The deposit, it will 85 be noticed, is continuous. When the wires have been thus increased sufficiently in size, they are removed and drawn by any well-known process of drawing wire, and sufficient 90 portions of the small wire thus formed may be employed to supplant those originally employed for receiving the deposit where homogeneous wire is to be produced. Compound 95 wire—that is, a wire having a core of one metal, such as steel, for instance, and an outside of some other metal, such as copper—may be made in this manner. In this case the wires to compose the cores are employed for receiving the deposit.

I claim as my invention—
The combination, substantially as hereinbefore set forth, of an electro-deposition vat, a series of endless wires, portions only of each 5 of which are in the vat at any time, means for passing the same continuously through the vat, and two series of horizontal anodes, one series being above and the other series below the wires.

In testimony whereof I have hereunto subscribed my name this 3d day of June, A. D. 1885.

MOSES G. FARMER.
